UNITED STATES PATENT OFFICE.

BARTLETT BOLLING, JR., OF CHARLOTTE, NORTH CAROLINA.

METHOD OF AND MEANS FOR SEPARATING GRANULAR MATERIAL.

Application filed April 22, 1921. Serial No. 463,671.

To all whom it may concern:

Be it known that I, BARTLETT BOLLING, Jr., a citizen of the United States, residing at Charlotte, in the county of Mecklenburg and State of North Carolina, have invented certain new and useful Improvements in Methods of and Means for Separating Granular Material, of which the following is a specification.

10 This invention relates to a method of and means for separating granular material containing pieces of different specific gravity, and has special utility when applied to the separation of coke from clinker, in the recovery of combustible matter from coal ashes.

15 The general objects of the invention are to provide an improved method of and means for handling, screening and grading the material, and an improved hydraulic classifier, by means of which the graded material may be classified or separated into its constituents of different specific gravity. In the case of coal ashes, these separated constituents represent the combustible and the incombustible 25 portions.

20 Other and more specific objects will appear from the following description, and the novel features will be pointed out in the appended claims.

30 In order that the principles underlying the invention may be clearly understood, reference is had to the accompanying drawings, illustrating one arrangement of apparatus by means of which the invention may be carried out, and forming part of this specification. In these drawings:—

35 Figure 1 is a sectional elevation showing my improved arrangement of separating tank and associated parts;

40 Figure 2 is a plan view of the same;

45 Figures 3 and 4 are enlarged fragmentary sectional elevations taken on planes at right angles to each other, illustrating the details of my improved hydraulic classifier and the method in which it operates;

50 Figure 5 is a plan view of a plant arranged for reclaiming combustible matter from coal ashes, according to my improved method, and

55 Figures 6 and 7 are respectively end and side elevations of such a plant, some unimportant elements being omitted for the sake of clearness.

Reference will first be had particularly to Figs. 1 to 4, inclusive, and my improved hydraulic classifier itself will be explained

in detail. As shown in these figures, I provide a tank 1 which may be of any suitable size, shape or construction, being illustrated here as of rectangular shape, and provided with a hopper bottom 2. Although as will hereinafter appear it is not necessary that this tank be closed, it is shown in the drawings as provided with a tight top or cover 3. Fitting closely through this cover, or otherwise suitably supported, is a receptacle 4 which constitutes my hydraulic classifier, proper. This receptacle is preferably in the form of a tapering circular bucket and is provided in the center of its bottom with a circular opening or orifice 5. It will be noted that this bucket or receptacle is relatively small, it having been found in practice that good results can be obtained from a receptacle of three or four gallons capacity. The tank 1 on the other hand is preferably relatively large, for reasons which will hereinafter appear.

50 The receptacle 4 is, as above stated, supported above the tank in such a way that its interior communicates with the interior of the tank through the opening 5. If the tank is entirely closed by means of a tight fitting top, the one requirement is that the receptacle 4 be supported by such top, so as to make a water-tight joint. If, as will hereinafter appear, the tank 1 is not entirely closed, the receptacle 4 should be immersed in the tank, as shown in the drawings to such an extent that its upper edge or rim 6 is below the upper edge of the open portion of the tank.

55 The upper edge or rim of the receptacle 4 is surrounded by a wall 7 which may be either circular, or rectangular as shown in Figure 2, such wall constituting with the top 3 of the tank, an annular basin or launder. This is provided at one side with a discharge trough or conduit 8 which projects beyond the side of the tank and is arranged to deliver into a suitable box or container 9. This container is provided at its bottom with a strainer 10 adapted to permit the water to escape into a pipe 11, and is preferably also equipped with a conveyor 12 for carrying away the granular material as it accumulates on the strainer.

60 As shown in Figures 1 and 2 of the drawing, the wall 7 is continued as indicated at 13 to form with the side of the trough 8 an enclosure around an opening or well 14, through which a suitable conveyor 15 oper-

ates, for the purpose of continuously removing the solid material which collects in the bottom of the tank. Referring, therefore, particularly to Figures 1 and 3 it will be noted that the wall 13 surrounding the opening 14 extends above the top edge or rim 6 of the receptacle 4. Therefore, when water is poured into the receptacle as herein-after described it will be passed through the opening 5 and fill the tank, the water rising in both the tank and the receptacle until the level reaches the point indicated by the line 16 in Figures 1 and 3, at which point, the water will begin to overflow the top of the receptacle and escape through the trough 8. In operation, therefore, if, as shown in the drawings, an open tank is employed, the water level in such tank will be maintained at a height slightly above the upper edge 20 of the receptacle 4.

The material to be separated, which is in granular form, is fed to the classifier at a uniform rate, by means of a screw or other conveyor 17, and is delivered by such conveyor onto the surface of the water in said receptacle, preferably substantially at the center thereof. The end of the conveyor is disposed at a short distance above the surface of the water as shown in the drawings.

In order to effect the separation of the heavy and light particles constituting the material to be treated, I pour or cause to fall upon the surface of the water in the receptacle 4, and preferably substantially at the center thereof, and at a point co-inciding with the point of delivery of the granular material, a continuous steady stream of water as indicated at α . While this water may in some cases be delivered from an ordinary pipe, I have found that much better results are obtained where the stream falls, cascade fashion, from the end of a conduit, through which the water flows very slowly and is comparatively quiet. To this end, I provide a relatively large trough 18, which may be either of rectangular or other section, and deliver into the distant end thereof water from a supply pipe 19, controlled by a valve 20. By means of the valve the rate of flow 50 can be regulated as desired, and, since the trough 18 is larger than the pipe 19 and is substantially horizontal, the water flows quietly and slowly through such trough, as indicated at w , pouring out of the end thereof, in the form of a solid quiescent stream, practically without air-bubbles. The conduits 17 and 18 for conveying the material and water to the classifier, radiate from a common center, such center being approximately the axis of the receptacle 4, and as shown in the drawings these conduits are preferably disposed at substantially right angles to each other. Owing to the relation of their delivery ends, it will be seen that 65 the material to be treated is discharged onto

the surface of the water in the receptacle substantially in the path of the stream of water falling from the trough 18.

In the drawings I have designated the lighter pieces by a and the heavier pieces by b . As the falling stream of water x strikes the surface of the water at y and encounters the stream of material to be treated, the force of the falling water, acting with gravity, carries the heavier particles b straight downward through the receptacle and discharges them through the orifice 5 in the bottom thereof, into the tank 1, while the lighter particles a tend to become deflected from a vertical path and drift out 70 toward the sides, where they are caught by the upflowing water currents or eddies and carried over the rim of the receptacle with the overflowing water, at z , as indicated by the arrows. It will be understood that the 75 momentum of the falling stream x causes descending and more or less diverging currents in the central part of the receptacle 4, and these currents are deflected by the bottom 4^a and directed upwardly along the 80 sides of the receptacle. Looking at the action from another view point, the bottom 4^a may be said to constitute an annular flange surrounding the orifice 5 and serving as a 85 baffle to deflect the currents. The lighter 90 material a which passes over the rim of the receptacle with the water, is caught in the surrounding basin or launder and discharged through the trough 8 into the box 9. Here the water is separated and the material carried away by the conveyor 12. The 95 heavier material b passing downwardly through the opening 5, settles to the bottom 100 of the tank 1 and is carried away by the conveyor 15.

In order to insure an absolutely uniform flow of water through the trough 18, the pipe 19 through which such water is supplied, leads from an elevated reservoir 21, in which the water is maintained at a constant level. 22 designates a pipe through which water under pressure is supplied to such reservoir, and the end of this pipe is provided with a float operated valve 23. In this way the reservoir is kept filled to a definite level, and a constant head for forcing water through the pipe 19 thus maintained.

The above described method and apparatus is particularly efficient in separating partially coked coal from the clinker or incombustible material found in coal ashes. The fine ash having been removed, and the remaining mixture of coke and clinker having been graded, as hereinafter described, into portions of substantially uniform size, such 115 material is fed to the classifier. The coke, which must be in a substantially dry state, is so light that much of it immediately floats off, upon striking the surface of the water. The rest of it, is carried downward into the 120

125 130

water to a greater or less depth, as indicated in Figs. 3 and 4, and then passes upward and over the edge of the receptacle, while the clinker and other more or less silicious material escapes through the opening 5 into the tank. I have found that with the various parts properly proportioned and adjusted, not more than 5% of the coke will find its way down through the opening 5, 10 the remaining 95% being carried over the edge, and recovered.

While the size of the stream of water, and the height of the trough 18 above the receptacle, as well as the rate of delivery of 15 the material to be treated, will vary under different conditions, I have found that a height from ten to fifteen inches above the receptacle gives good results. By way of example, I may state that I have produced 20 very satisfactory separation by feeding the mixture of coke and clinker into the separator at about the rate of two tons an hour, while at the same time employing a stream of water running approximately twenty gallons a minute. As above stated, these figures 25 are illustrative only and vary between wide limits in accordance with the nature and size of the granular material.

While, of course, the above described 30 method and apparatus for separating or classifying granular material is in no sense limited for use in connection with coal ashes, still I have found it especially applicable for such a purpose, and in Figures 35 5, 6 and 7, I have illustrated more or less conventionally a convenient and novel system for recovering combustible matter from the coal ashes in accordance with the above described method.

40 Referring to these figures, it will be seen that I have illustrated a shed under which the necessary apparatus is housed, such apparatus including the elevated reservoir 21. As hereinafter described, a series of washers 45 or hydraulic classifiers is employed, and the waste pipe 11 from each of these washers is connected with a common pipe which delivers into a settling basin 24. The water accumulating in this basin is returned by 50 means of a pump 25 and pipe 26 to the elevated reservoir 21, to be used over again. In this way the water supply is conserved.

An elevated track 30 is provided extending 55 from the ash shed or other dump, and on this track runs a car 31, preferably of the side-dump variety, which is adapted to deliver the ashes, as they come from the ash pit, into a hopper, 32. From the hopper 32, the ashes move by gravity into one end of 60 a long rotary screen 33. As clearly shown in Fig. 5, this screen is made up of a number of sections *c*, *d*, *e* and *f* of gradually increasing mesh. The first section *c* is very fine, preferably approximately $\frac{1}{16}$ ", and the 65 fine ash and dust which passes through this

section is collected in a hopper *C*, from which it may be drawn through a suitable chute 38 and disposed of in any desired manner. In many cases it is found that this fine dust contains a high percentage of combustible matter and may be advantageously again fed to the stokers. The sections *d*, *e* and *f* of the screen are preferably of $\frac{1}{4}$ ", $\frac{3}{8}$ " and $1\frac{1}{2}$ " mesh, respectively, and the material passing through these sections is 70 collected, respectively, in hoppers *D*, *E* and *F*. The material comprising pieces over $1\frac{1}{2}$ " in size, which pass out of the right hand end of the screen as seen in Figure 5, may be delivered upon a traveling belt or apron 80 37, and as the material moves along on this belt it may be hand-picked to remove the clinker. The screen may be rotated by means of a belt 35 passing over a pulley 34 on the screen shaft, and another pulley 85 36 on a power shaft running lengthwise of the shed and driven by any suitable means.

The material in each of the three hoppers *D*, *E* and *F* is, therefore, made up of pieces or particles of substantially uniform size. 90 This material is carried from the hoppers to corresponding elevated bins *D'*, *E'* and *F'*, by means of conveyors 39. These conveyors pass over pulleys mounted on a shaft 40 driven by a belt 41 from the power shaft 95 36. It will be noted that the bin *F'* is shown as considerably larger than the other two, and this is due to the fact that the material made up of inch and a half pieces is considerably more bulky than the finer material. 100

From each bin extends a screw or other conveyor 17 to a hydraulic classifier, such as shown in detail in Figs. 1 to 4, and the reclaimed coke or combustible material collected from the boxes 9 may be conveyed to bunkers and fed again to the stokers, either alone or mixed with fresh fuel. The incombustible silicious material or clinker is practically free from combustible matter 105 and may be conveyed from the bottom of the tanks 1 to suitable depositories and employed advantageously for various purposes, such as the making of concrete.

In addition to operating upon ashes taken 110 directly from the ash pit, I also contemplate reclaiming combustible material from old ash dumps. In this case, however, it will be necessary to first dry the material.

My improved method, therefore, so far as 120 the treatment of ashes is concerned, is to first screen out the fine dust and then grade the remaining material into uniform portions of different sizes, before feeding it to the classifiers. To get the best results, this 125 material must be fed to the classifiers in a substantially dry condition.

It will, therefore, be seen that I have devised an improved method and apparatus for separating granular material containing 130

pieces of different specific gravity by means of a hydraulic classifier, and it is thought that the many advantages of my invention will be readily appreciated by those familiar with such matters, without further discussion.

What I claim is:

1. The herein-described method of separating granular material containing pieces of different specific gravity, which comprises feeding such material at a uniform rate into a receptacle having an unobstructed opening in its bottom, and maintained full of water, and at the same time continuously pouring upon the free surface of the water in such receptacle immediately above the opening a uniform stream of water, in the form of a cataract, whereby the water overflowing the brim of the receptacle is caused to carry with it the lighter pieces, while the heavier pieces pass continuously downward through the opening in the bottom of the receptacle.

2. The herein-described method of separating granular material containing pieces of different specific gravity, which comprises causing a steady stream of water to fall from a predetermined height into a receptacle having an unobstructed opening in its bottom, but maintained full of water, and feeding the material at a uniform rate upon the free surface of the water in such receptacle substantially in the path of the falling water, whereby the lighter material is carried away by the water overflowing the upper edge of the receptacle, and the heavier pieces constantly escape through the opening in the bottom.

3. The herein-described method of separating granular material containing pieces of different specific gravity, which comprises providing a receptacle having an unobstructed opening in its bottom but maintained full of water, and continuously causing to fall upon the surface of the water in said receptacle simultaneously and at substantially the same point a steady stream of the material to be treated, and a constant stream of water, whereby the heavier pieces are expelled through the opening in the bottom, and the lighter pieces are carried over the edge of the receptacle by the water.

4. The herein-described method of separating granular material containing pieces of different specific gravity, which comprises providing a circular receptacle having an unobstructed central opening in its bottom, but maintained full of water, and continuously causing to fall upon the surface of the water in such receptacle simultaneously and at substantially the same point a steady stream of the material to be treated, and a constant stream of water, whereby the heavier pieces are expelled through the opening in the bottom, and the

lighter pieces are carried over the edge of the receptacle by the water.

5. The herein-described method of separating granular material containing pieces of different specific gravity, which comprises providing a circular, downwardly tapering receptacle having at its small end a bottom provided with a central opening, maintaining such receptacle full of water, and continuously causing to fall upon the surface of the water in said receptacle simultaneously and at substantially the same point a steady stream of the material to be treated, and a constant stream of water, whereby the heavier pieces are expelled through the opening in the bottom, and the lighter pieces are carried over the edge of the receptacle by the water.

6. The herein-described method of separating granular material containing pieces of different specific gravity, which comprises causing a quiescent solid stream of water to fall from a predetermined height into a receptacle having an unobstructed opening in its bottom, but maintained full of water, and feeding the material at a uniform rate onto the surface of the water in such receptacle substantially in the path of the stream of falling water, whereby the lighter pieces are carried over the edge of the receptacle with the overflowing water, while the heavier pieces escape through the opening in the bottom.

7. The herein-described method of separating granular material containing pieces of different specific gravity, which comprises feeding the material at a uniform rate onto the surface of the water in a receptacle maintained full of water but provided with an unobstructed opening in its bottom, and delivering a steady stream of water into the top of said receptacle in such manner as to create currents tending to cause the lighter pieces to be carried out over the brim of the receptacle, while the heavier pieces are constantly discharged through the opening in the bottom.

8. The herein-described method of separating coke from clinker which comprises causing a steady stream of water to fall from a predetermined height into a receptacle having an unobstructed opening in its bottom, but maintained full of water, and feeding the mixture of coke and clinker in a dry state and at a uniform rate into the top of such receptacle substantially in the path of the falling water, whereby the coke floats or is carried over the edge of the receptacle by the overflowing water, while the clinker passes downwardly and escapes through the opening in the bottom.

9. The herein-described method of recovering combustible matter from coal ashes which consists, first, in removing the fine ash from the mass; second, dividing the re-

sulting granular material comprising coke and clinker into graded sizes; third, feeding each uniform grade of mixed coke and clinker at a uniform rate into the top of a 5 receptacle having an unobstructed opening in its bottom but maintained full of water; fourth, causing a steady stream of water to fall from a predetermined height into said receptacle in such manner as to create currents 10 tending to cause the coke to be carried out over the brim of the receptacle while the clinker is constantly discharged through the opening in the bottom.

10. A hydraulic classifier comprising a 15 receptacle having a bottom provided with a central unobstructed opening, a tank over which said receptacle is supported, means forming a conduit extending from the upper edge of said receptacle to a point beyond the 20 side walls of said tank, means for feeding into the top of said receptacle at a point immediately above the central opening in the bottom thereof water and the material to be classified, and means for causing water 25 to continuously overflow the said upper edge of said receptacle into said conduit.

11. A hydraulic classifier comprising a receptacle having a bottom provided with a central opening, a tank over which said receptacle is supported; means for constantly feeding into the top of said receptacle at a point immediately above the central opening in the bottom thereof, water and the material to be classified, and means for maintaining 30 said tank filled with water up to a level above the upper edge of said receptacle, whereby water continuously overflows such edge.

12. A hydraulic classifier, comprising a 40 receptacle having an unobstructed opening in its bottom, a tank of water in which the bottom of said receptacle is immersed, means for preventing the water in the tank from enveloping the upper edge of said receptacle, 45 means for continuously feeding into the top of said receptacle water and the material to be classified so that a mixture of water and material overflows said upper edge, and means for directing this overflow into a suitable container.

13. A hydraulic classifier comprising a receptacle having an unobstructed opening in its bottom, a tank over which said receptacle is mounted and with which it communicates 50 through the top of said opening, an annular basin surrounding the upper edge of said receptacle, and separating it from the interior of said tank, means for continuously feeding into said receptacle 55 water and the material to be classified, and means for causing part of such material, mixed with water, to overflow said free upper edge of the receptacle into said basin.

14. In a hydraulic classifier the combination 60 with a receptacle having an opening

in its bottom, of means for continuously feeding into the top of said receptacle water and the material to be classified, an open tank in which said receptacle is immersed, means for maintaining the water level in 70 said tank above the upper edge of said receptacle, whereby water constantly overflows such upper edge, carrying with it part of such material, while another part passes downwardly through said opening into said 75 tank, and means for continuously removing such material from said tank.

15. In a hydraulic classifier the combination with a receptacle having an opening in its bottom, of means for continuously feeding into the top of said receptacle water and the material to be classified, a tank with which said receptacle communicates through 80 said opening, means for causing the lighter portion of such material, mixed with water, 85 to overflow the upper edge of said receptacle, while the heavier portion passes downwardly through such opening into said tank, and means for continuously removing such heavier material from said tank.

16. A hydraulic classifier comprising a circular receptacle having a restricted unobstructed central opening in its bottom, a tank with which said receptacle directly communicates through said opening, means 95 preventing contact of the upper edge of said receptacle with the contents of said tank, and means for feeding water and material into the top of said receptacle and causing the mixture to overflow the said upper 100 edge thereof.

17. A hydraulic classifier comprising a circular tapering receptacle having an unobstructed central opening in its bottom, a tank with which said receptacle directly 105 communicates through said opening, and means for feeding water and material into the top of said receptacle and causing the mixture to overflow the upper edge thereof.

18. A hydraulic classifier comprising a 110 circular receptacle provided with an internal annular flange forming a restricted passageway, a tank with which said receptacle directly communicates through said passageway, and means for feeding water and material 115 into the top of said receptacle and causing the mixture to overflow the upper edge thereof.

19. A hydraulic classifier comprising a receptacle having an unobstructed but restricted opening in its bottom, an annular basin surrounding the upper portion of said receptacle, the upper edge of said receptacle projecting above the bottom of said basin, a tank over which said receptacle and basin 120 are supported in such position that the upper edge of the receptacle is below the upper edge of the tank, and means for feeding water and material to be separated into 125 the top of said receptacle and causing a part 130

of the mixture to overflow the upper edge thereof.

20. A hydraulic classifier comprising a receptacle having a flange projecting inwardly from the side walls thereof, such flange constituting a bottom or closure with an opening therein, a tank with which said receptacle directly communicates through said opening, said receptacle and tank being filled with water, and means for continuously and simultaneously causing to fall upon the surface of the water in said receptacle at a point immediately above said opening, a stream of water, and a separate stream of material to be classified, whereby the heavier pieces pass downwardly through said opening, while the lighter portions are deflected upwardly by said flange and caused to flow, with the water, over the upper edge of the receptacle.

21. In a hydraulic classifier, the combination with a receptacle, and means for feeding thereinto the material to be classified, of a substantially horizontal conduit with one end positioned directly over said receptacle, and means for continuously supplying water to the other end of said conduit through a restricted opening and under a constant head whereby such water falls into said receptacle in a solid quiescent stream.

22. In a hydraulic classifier, the combination with a tank, of a receptacle having an opening in its bottom communicating with said tank, said receptacle and tank being filled with water, and means for continuously and simultaneously causing to fall upon the surface of the water in said receptacle a stream of water and a separate stream of

the material to be classified, in such manner that the lighter pieces, mixed with water, overflow the top of the receptacle, while the heavier pieces pass through said opening into the tank.

23. A hydraulic classifier comprising a separating receptacle maintained full of water and having a bottom provided with an opening, means for feeding at a uniform rate on to the surface of the water in said receptacle the material to be separated, and means for constantly pouring a steady stream of water onto the surface of the water in said receptacle at a point immediately above the opening in the bottom thereof.

24. A hydraulic classifier comprising a separating receptacle maintained full of water and having a bottom provided with an opening, means for pouring upon the surface of the water in said receptacle two constant streams, one of water, and the other of the material to be separated, said two streams co-inciding, where they strike the surface of the water, at a point immediately above the opening in the bottom of the receptacle.

25. A hydraulic classifier comprising a circular receptacle maintained full of water but having a central opening in its bottom, and two conduits terminating above the top of said receptacle and adapted to pour upon the free surface of the water therein two separate streams, one of water, the other of the material to be classified, said conduits radiating from the axis of said receptacle.

In testimony whereof I affix my signature.

BARTLETT BOLLING, Jr.
